UNITED STATES PATENT OFFICE.

CARLTON H. DUNFEE AND ADAM L. SPENCE, OF WRIGHTSTOWN, NEW JERSEY; SAID DUNFEE ASSIGNOR TO SAID SPENCE.

GASOLINE-TANK FILLER AND INDICATOR.

Application filed January 10, 1922. Serial No. 528,131.

To all whom it may concern:

Be it known that we, CARLTON H. DUNFEE and ADAM L. SPENCE, both citizens of the United States, and both residing at 5 Wrightstown, county of Burlington, State of New Jersey, have invented a new and useful Gasoline-Tank Filler and Indicator, of which the following is a specification.

Our invention consists of novel means 10 adapted to be readily installed upon or attached to the gasoline tanks of automobiles of any conventional type, wherein said tank is located under the front seat, and wherein it is now necessary for the occupant to stand 15 up and remove a seat cushion before the tank can be filled, means being provided for enabling the height of the gasoline level to be readily ascertained by a novel indicating device, and provision being made for enabling 20 an attendant to readily refill the tank from the exterior of the automobile without disturbing the occupants of the seat above the tank or removing the seat cushions, below which the tank is located.

25 It further consists of a novel construction of indicating device and a novel construction of a closure for the outer end of the filling pipe.

With the above-mentioned and other objects in view, the invention consists in a filling conduit of novel construction and provided with a novel inlet portion having contents-indicating appliances arranged so as to be observable at all times; and the invention 35 consists also further in the novel and useful construction and parts and combinations and arrangements thereof, as herein-after described and further defined in the appended claims.

40 For the purpose of illustrating our invention, we have shown in the accompanying drawings a form thereof which is at present preferred by us, since it will give in practice satisfactory and reliable results, although it is to be understood that the various instrumentalities of which my invention 45 consists can be variously arranged and organized and that my invention is not limited to the precise arrangement and organization 50 of these instrumentalities as herein shown and described.

Figure 1 represents a perspective view of a gasoline tank filler and its adjuncts, embodying our invention.

55 Figure 2 represents on an enlarged scale, a

vertical sectional view of the gasoline tank filler and indicator, the section being taken on line 2—2 of Figure 1.

Figure 3 represents a perspective view of the outer end of the filling pipe and a portion 60 of the indicator mechanism.

Figure 4 represents a plan view of Figure 3.

Similar numerals of reference indicate 65 corresponding parts.

Referring to the drawings,

1 designates a gasoline tank having in its top 2 a threaded bushing 3 of the usual type, said bushing being ordinarily closed by a suitable cap or plug, which is unscrewed 70 when it is desired to fill the tank with gasoline. In carrying out our invention, we remove the cap and screw into said bushing the exteriorly threaded portion 4 of a short elbow or angular section of pipe or tubing 5, 75 which is composed of the vertical section 6 and the horizontal section 7, the latter being in practice about four inches long and serving as a handle to screw the vertical section or member 6 into place in the bushing 3. The section 7 terminates in the slightly enlarged exteriorly threaded head 8 against which abuts the enlarged exteriorly threaded head 9 of the section 10, which 80 heads are secured in assembled position by 85 the coupling 11, said coupling and heads being provided with right and left hand threads, so that as said coupling is turned, said heads will be brought into juxtaposition and a fluid tight joint will be formed as 90 seen in Figure 2. The pipe 10 passes through the hole 12 in the side 13 of the car and terminates in the upturned end 14, having the flange 15 thereon.

16 designates a threaded pin or bolt 95 screwed into said flange and passing through the cap or disk 17, which can be turned laterally upon said pin as an axis. The disk 17 has a hook 18 thereon diametrically opposite to the pin 16 which is engaged by the 100 pin 19, which has a wing nut 20, which, when tightened, will clamp the disk 17 tightly into place.

21 designates a ring through which the pipe 10 passes which is employed to conceal 105 the hole 12 and is fastened to the side 13 by screws or the like.

The float 22 is supported from the vertical portion of the flexible connection 23, which is attached to the bell crank 24, from which 110

leads the horizontal wire 25 to the connection 26, which is connected with the stem 27 of the indicator, which carries the pointer 28 which coacts with the dial 29, so that as 5 the float rises and falls the pointer and dial will indicate the height of the gasoline.

The seat cushion 30 is on the top of the tank 1, and it will be understood that the filling pipe sections 7 and 10 lie closely 10 against the top of the tank, and afford no obstruction to the seat cushions fitting there-against in the usual manner.

Our device in practice is assembled by first screwing the section 5 into place. The 15 coupling 11 is then secured on the head 8. The section 10 is next inserted through the hole 12 and screwed into the coupling, which is then tightened and the finishing ring 21 is then secured in position.

20 When it is desired to fill the tank the wing nut 20 is loosened and the closure 17 swung to one side and after the tank is filled said closure is turned into the position seen in Figures 3 and 4 and the wing nut tightened. 25 By our invention, the filling of the gasoline tank can be readily effected from the exterior of the car without necessitating the occupants of the front seat arising or disturbing the front seat cushions, making our in- 30 vention especially desirable in closed cars, as coupes and sedans, and the like.

It will be apparent that we have devised a novel and useful gasoline tank filler and indicator, which embodies the features of 35 advantage enumerated as desirable in the statement of the invention and the above description, and while we have, in the present instance, shown and described a preferred embodiment thereof which will give in practice satisfactory and reliable results, it is 40 to be understood that such embodiment is susceptible of modification in various particulars without departing from the spirit or scope of the invention or sacrificing any 45 of its advantages.

Having thus described our invention, what we claim as new and desire to secure by Letters Patent, is:—

1. In a device of the character stated, an 50 elbow having a vertical exteriorly threaded section adapted to be screwed into the top of a gasoline tank, and a horizontal extension adapted to serve as a handle and having an exteriorly threaded head; another pipe 55 section forming a continuity of said horizontal extension and having an outer exteriorly threaded head and terminating in

an upturned filling opening located exteriorly of the car body, an interiorly threaded coupling engaging said threaded heads, the latter and said coupling having right and left-hand threads, and a closure for said filling opening. 60

2. In a device of the character stated, an elbow having a vertical exteriorly threaded section adapted to be screwed into the top of a gasoline tank and a horizontal section adapted to serve as a handle and having an exteriorly threaded head, another pipe section having an exteriorly threaded head and an upturned filling terminal, an internally threaded coupling engaging said threaded heads, the latter and said coupling having right and left-hand threads, a flange for 70 said terminal, a closure hinged to said flange, 75 and means for clamping said closure upon said flange to make a tight joint.

3. In a device of the character stated, an elbow having a vertical exteriorly threaded section adapted to be secured into the top 80 of a gasoline tank and a horizontal section adapted to serve as a handle, and having an exteriorly threaded head, another pipe section having an exteriorly threaded head and an upturned filling terminal, a coupling 85 engaging said head, a flange on said terminal, a pin on said flange, a disk through which said pin passes, a hooked recess on said disk, a threaded pin on said flange and engaging the walls of said recess, and a nut 90 on said last-mentioned pin for clamping said disk in place.

4. In a device of the character stated, an elbow having a vertical exteriorly threaded section adapted to be screwed into the top 95 of a gasoline tank, and a horizontal extension adapted to serve as a handle and having an exteriorly threaded head, another pipe section having an exteriorly threaded head and terminating in an outer upturned filling 100 opening located exteriorly of the car body, an interiorly threaded coupling engaging said threaded heads, the latter and said coupling having right and left-hand threads, and a closure for said filling opening, in 105 combination with an indicating device located in proximity to said filling opening, a float and connections from the latter to said indicating device.
